**APPARATUS FOR REMOVING STRANDS
FROM ARTICLES**

Richard C. Kirchmeyer and Warren E. Petersen, Omaha, Nebr., assignors to Western Electric Company, Incorporated, New York, N.Y., a corporation of New York
Filed Dec. 21, 1962, Ser. No. 246,400
10 Claims. (Cl. 242—129.6)

This invention relates to apparatus for removing strands from articles, and more particularly to apparatus for removing strands from a plurality of cylindrical reels in unison. It is an object of this invention to provide new and improved apparatus of this character.

In the manufacture of insulated wire and cable, insulated wire is wound on cylindrical reels, and subsequently is unwound from the reels, in various stages of the manufacturing process. In many instances after an unwinding operation, some of the reels involved have unused wire remnants thereon which must be removed from the reels before the reels can be reused. In the past, these scrap wire remnants have been removed from the reels by unloading the reels by hand from vertically nested pallets upon which they normally are stored, removing the wire remnants from the reels, and then loading the reels by hand back on the pallets. This procedure is undesirable since it is relatively inefficient, uneconomical and time consuming.

Accordingly, another object of this invention is to provide new and improved apparatus for removing wire remnants from a plurality of reels supported on vertically nested pallets, without removing the reels from the pallets.

A further object of this invention is to provide new and improved apparatus for removing wire remnants from a plurality of reels in unison, where the reels are supported on vertically nested pallets which are movable laterally relative to one another.

A still further object of this invention is to provide new and improved apparatus for removing strands from a plurality of reels in unison, where the reels have bores extending therethrough and are supported on a pallet in a row with the bores substantially in axial alignment.

In accordance with the invention, a mechanism moves a set of pallets having reels supported thereon against a stop mechanism to position the pallets such that bores in the reels are aligned axially with horizontal, parallel arbors. The arbors then are moved into the bores in the reels and lifted vertically to lift the reels off the pallets so that the reels can rotate on the arbors and so that strands on the reels, such as scrap wire remnants, can be pulled from the reels.

In a preferred embodiment of the invention, a conveyor arrangement is provided for moving a set of vertically nested pallets with rows of reels thereon into and out of position adjacent an arbor assembly which includes vertically spaced, parallel arbors connected together for movement as a unit. The pallets are engaged and moved into position adjacent the arbors by a vertically arranged frame assembly against a vertically arranged stop mechanism to orient the pallets such that bores in the reels are aligned axially with the arbors, whereby the arbors can be moved longitudinally through the bores.

Vertically spaced, horizontal support members are provided for supporting the arbors between their ends when the arbors have been moved through the bores in the reels. The support members are connected together for vertical movement at adjacent ones of their ends while other ends thereof, which extend adjacent the frame assembly, normally are unconnected so as not to

2

interfere with movement of the pallets by the frame assembly into position adjacent the arbors. As the frame assembly moves the pallets adjacent the arbors a vertically movable mechanism on the frame assembly engages and interconnects the unconnected ends of the support members, and also engages and connects itself to a lifting apparatus so that it can be lifted thereby.

The lifting apparatus also is connected to lift the support members at their connected ends and to lift vertically movable guide and support assemblies for the arbors. Thus, after the arbors have been moved through the bores in the reels, operation of the lifting apparatus lifts the arbors and thereby lifts the reels off the pallets so that the reels can rotate on the arbors, after which strands on the reels, such as scrap wire remnants, are pulled therefrom by rotatable winding apparatus connectable to the strands.

This invention, together with further objects and advantages thereof, will best be understood by reference to the following detailed description, taken in connection with the accompanying drawings in which:

FIG. 1 is a side elevational view of the strand removing apparatus in a first operating position, certain parts having been omitted;

FIG. 2 is an elevational view taken substantially along the line 2—2 of FIG. 1, but showing the strand removing apparatus in a second operating position;

FIG. 3 is an enlarged partial cross-sectional view taken substantially along the line 3—3 of FIG. 2;

FIG. 4 is an enlarged partial cross-sectional view taken substantially along the line 4—4 of FIG. 2;

FIG. 5 is a partial elevational view taken substantially along the line 5—5 of FIG. 3;

FIG. 6 is a partial plan view of the strand removing apparatus;

FIG. 7 is a partial cross-sectional view showing a detail of the apparatus; and

FIG. 8 is a partial cross-sectional view showing a detail of the apparatus.

Referring to FIGS. 1 and 2 of the drawings, it is seen that the illustrated embodiment of the invention is designed to remove scrap wire remnants 10 (shown only in FIG. 2) from a plurality of cylindrical reels 11 in unison. The reels 11 are supported on sets (only one shown) of vertically nested box-like pallets 12 in elongated substantially V-shaped troughs 13 (FIG. 1) of the pallets, and the troughs of each pallet extend substantially parallel to one another. Each of the reels 11 includes an axial cylindrical bore 14 (FIG. 1) which receives an arbor to support the reel for rotation during a scrap wire removing operation, and which in actual use receives an arbor for supporting the reel for rotation during wire and cable manufacturing operations.

Each of the pallets 12 includes vertical corner members 16 and a plurality of other frame members suitably secured to one another to form a substantially open-sided rectangular container. The sides and ends of each pallet 12 at its top include outwardly and upwardly projecting L-shaped flanges 17 which form a nest for receiving the bottom of another pallet so that the pallets can be vertically nested as shown in FIGS. 1 and 2. To facilitate the positioning of the pallets 12 in nested relationship, the inner dimensions of the nests of the pallets are larger than the outer dimensions of the bottoms of the pallets, and thus the nested pallets are movable horizontally relative to one another. Accordingly, the axes of the cylindrical bores 14 in the reels 11 in any one pallet 12 normally are not in vertical alignment with the axes of the bores in the reels in the other pallets.

Each set of vertically nested pallets 12 is movable to and away from the apparatus on a main horizontal roller

conveyor 18, which can be seen extending along the bottom of FIG. 2. Referring to FIG. 2 and the lower right-hand side of FIG. 1, it is seen that the roller conveyor 18 includes a movable conveyor section 19, which is of a length such that it can receive one of the sets of pallets 12 thereon. The conveyor section 19 is movable from the position shown in FIG. 1 to the left along a cross conveyor 21, for moving the pallets 12 between first and second arbor assemblies 22 and 23 for a scrap wire removing operation, the arbor assemblies being located on opposite sides of the apparatus, as is best shown in FIGS. 2 and 4.

The movable conveyor section 19 includes a pair of parallel rows of rollers 24 (FIGS. 1 and 2) extending along opposite sides of a rectangular horizontal base plate 25 (FIG. 2). Each row of rollers 24 is mounted on the base plate 25 between inner and outer upstanding parallel flanges 26 and 27 secured to the base plate at their lower ends.

As is best shown in FIG. 2, the base plate 25 of the conveyor section 19 is supported for movement on the cross conveyor 21 on a pair of horizontally spaced parallel rows of rollers 28. Each row of rollers 28 is mounted on an upstanding leg of an angle bar 29 having its other leg secured to and along one side of a horizontal rectangular platform 31 resting on the floor.

At the right-hand end of the cross conveyor 21, as viewed in FIG. 1, a vertical frame 32 is mounted for horizontal movement for moving the conveyor section 19 and the set of vertically nested pallets 12 thereon horizontally along the cross conveyor. The vertical frame 32 includes a pair of spaced vertical side members 33 (FIGS. 1 and 4) and upper and lower horizontal cross members 34 suitably connected together in a substantially rectangular shape. The lower end of each of the vertical side members 33 carries a support wheel 36. The support wheels 36 are movable along the platform 31 on opposite sides of the cross conveyor 21 (FIG. 4) and the lower cross member 34 is spaced above the platform to permit travel of the frame above the cross conveyor.

Referring to the bottom of FIG. 2 and to FIG. 7, it is seen that the lower cross member 34 of the vertical frame 32 is connected to the conveyor section 19 by a suitable lost motion mechanism, such as a pair of horizontally spaced bolt and nut assemblies 37. Thus, as shown in FIGS. 1 and 7, the vertical frame 32 is movable to the right relative to the conveyor section 19 into spaced relationship therewith, in which position it will not interfere with movement of the pallets 12 along the main conveyor 18 onto the conveyor section.

As shown in FIG. 7, each bolt and nut assembly 37 includes an elongated bolt 38 extending through aligned apertures in depending lugs 39 and 41 on the base plate 25 of the conveyor section 19 and the lower cross member 34 of the vertical frame 32, respectively, the bolt being provided with a head on one end and a threaded nut on its other end which cooperate to limit the movement of the vertical frame relative to the conveyor section and which are spaced apart so as to permit such limited movement. Movement of the conveyor section 19 with the vertical frame 32 to the right beyond the position of the conveyor section shown in FIG. 1 is limited in any suitable manner, as for example by stop members (not shown) on the main conveyor 18.

The vertical frame 32 further includes vertically spaced channel-shaped members 42 secured to the vertical side members 33 and extending horizontally across the width of the frame between the side members. The members 42 include pallet engaging surfaces 43 which all lie in a vertical plane parallel to the longitudinal axes of vertically spaced, parallel arbors 44 and 46 of the arbor assemblies 22 and 23, respectively.

As is best shown in FIGS. 1, 3 and 6, the upper ends of the vertical side members 33 of the vertical frame 32

are connected to horizontally reciprocating piston rods of a pair of upper fluid operating cylinders 47 rigidly mounted on the underside of an elevated frame 48. Similarly, the lower ends of the side members 33 are connected to horizontally reciprocating piston rods of a pair of lower fluid operating cylinders 49 rigidly mounted on the platform 31 adjacent opposite sides of the cross conveyor 21. The operating cylinders 47 and 49 are connected to a common supply line and are operative to move the vertical frame 32 to the right into the position shown in FIG. 1, in which it is spaced from the conveyor section 19 as above described, and are operative to move the vertical frame to the left (FIG. 1) so that the frame engages the conveyor section 19 and so that the vertical surfaces 43 of the frame engage the adjacent vertical corner members 16 of the pallets on the conveyor section, to move the conveyor section and the pallets along the cross conveyor 21 into position between the arbors 44 and 46.

As is best shown in FIGS. 1 and 6, the elevated frame 48 is made up of a plurality of suitable members, certain of which at the ends thereof adjacent the corners of the frame, are bolted or otherwise suitably secured to the upper ends of vertical I-beam posts 51. The lower ends of the vertical posts 51 are anchored to the floor in any suitable manner.

As is best shown in FIGS. 2 and 4, the pair of vertical corner posts 51 at each side of the apparatus have a horizontal channel-shaped guide member 52 secured thereto adjacent their lower ends by suitable brackets. Each guide member 52 extends adjacent one side of the cross conveyor 21 obliquely inward toward the center of the apparatus and is engageable by the lower pallet 12 as the set of pallets is being moved between the arbors 44 and 46, for guiding the pallets toward the center of the apparatus and insuring their movement into engagement with a pair of vertically arranged stop assemblies 53 at the left-hand end (FIG. 1) of the cross conveyor.

As is best shown in FIG. 4, the stop assemblies 53 are located at opposite sides of the apparatus. Each of the stop assemblies 53 includes a vertical post 54, as for example an angle bar, secured at its lower end to the platform 31 (FIG. 1) and secured at its upper end to the elevated frame 48. Vertically spaced horizontal stop members 55 are fixedly mounted on each of the vertical posts 54 and each of the stop members includes a vertical stop surface 56. As in the case of the pallet engaging surfaces 43 of the vertical frame 32, the stop surfaces 56 all lie in a common vertical plane parallel to the longitudinal axes of the arbors 44 and 46. Further, the stop surfaces 56 are located so that when they are engaged by associated ones of the vertical corner members 16 of the pallets 12 on the conveyor section 19, as shown in FIG. 4, and in a manner next to be described, the pallets will be vertically aligned in planes parallel to the stop surfaces and the axes of the bores 14 in the reels 11 will be in axial alignment with associated ones of the arbors 44 and 46.

As the pallet engaging surfaces 43 of the vertical frame 32 engage the pallets 12 to move them between the arbors 44 and 46, the surfaces tend to rotate the pallets horizontally about their vertical axes so that the axes of the bores 14 in the reels 11 extend parallel to the longitudinal axes of the arbors, and also tend to align the pallets vertically in vertical planes parallel to the surfaces. Subsequently, as the pallets engage the stop surfaces 56 the pallet engaging surfaces 43 positively rotate the pallets about their vertical axes so that the bores 14 in the reels 11 extend parallel to the arbors 44 and 46, if the pallets are not so oriented, and the stop surfaces and the pallet engaging surfaces cooperate to align the pallets vertically to locate the bores in the reels in alignment with the arbors. The arbors 44 and 46 then can be moved from the retracted positions shown in dashed lines in FIG. 2 through the bores 14 into their positions shown in solid

lines in FIG. 2, either manually, or by a suitable mechanism (not shown).

The arbors 44 of the arbor assembly 22 are connected together for movement as a unit at their right-hand ends, as viewed in FIG. 2, by bolts which extend through apertures in a vertical connecting member 57 and which are threaded into the ends of the arbors. The arbors 46 of the arbor assembly 23 are similarly connected together at their left-hand ends (FIG. 2) by bolts and a vertical connecting member 58. Each of the arbor connecting members 57 and 58 carries a wheel 59 on its lower end which is supported on and movable along a track in the form of an elongated flat plate 61 integral with the platform 31 and resting on the floor.

As is best shown in FIGS. 3 and 4, each of the arbors 44 and 46 can be provided along its length with encircling rollers 62 which are mounted thereon adjacent one another for independent rotation, to facilitate rotation of the reels 11 on the arbors, and which are retained thereon by a nut member threaded on a threaded portion of the arbor at its free end.

Referring to FIG. 2, it is seen that the right-hand arbors 44 are supported for longitudinal movement in vertically movable guide assemblies 63, and the left-hand arbors 46 are supported in the same manner in vertically movable guide assemblies 64. As is best shown in FIGS. 3 and 4, each of the guide assemblies 63 and 64 includes a seven-sided tubular member 66 having longitudinally spaced sets of rollers 67 and shafts 68 mounted in opposite sides thereof to form supports for the arbor associated therewith. Each of the guide assemblies 63 and 64 also includes a vertical sleeve member 69 fixedly mounted on a bracket 71 secured to the tubular member 66 thereof. The sleeve member 69 is mounted for vertical sliding movement on a vertical cylindrical post 72 secured at its lower end to the platform 31 and secured at its upper end to a bracket fixedly mounted on one of the members of the elevated frame 48. Rotation of each of the guide assemblies 63 and 64 on its associated post 72 is prevented by a projecting lug 73 on the sleeve member 69 of the guide assembly being received between laterally spaced vertical guide flanges 74 (FIG. 4) on a collar member 76 adjustably mounted on the post beneath the sleeve member by suitable set screws.

As is best shown in FIGS. 1 and 2, a plurality of vertically spaced channel-shaped members 77 extend horizontally above the cross conveyor 21 centrally thereof and are designed to extend between adjacent ones of the reels 11 on the pallets 12, for supporting the arbors 44 and 46 between their ends when the arbors are lifted vertically by a lifting mechanism 78 supported on the top of the elevated frame 48 and subsequently to be described. For this purpose, the support members 77 are provided with apertures 79 (FIG. 1) for receiving the arbors 44 and 46 as the arbors are moved through the bores 14 in the reels 11.

The arbor support members 77 are rigidly connected together adjacent their ends farthest removed from the vertical frame 32 by vertical members 81, while the other ends of the support members adjacent the vertical frame are free and not connected to one another, so as not to obstruct movement of the pallets 12 between the arbors 44 and 46. Each of the support members 77 has a sleeve member 82 (FIGS. 2 and 4) secured thereto adjacent its connected end and supported for vertical movement on a vertical cylindrical post 83 secured at its lower end to the platform 31 and secured at its upper end to the elevated frame 48. As in the case of the sleeve members 69 of the arbor guide assemblies 63 and 64, each of the sleeve members 82 includes a laterally projecting lug 84 (FIG. 4) which extends between a pair of spaced vertical guide flanges 86 on a collar member 87 (FIG. 2) adjustably mounted on the post 83 beneath the sleeve member by suitable set screws, for preventing rotation of the

sleeve member and its associated support member 77 on the post.

The vertical frame 32 carries a vertically movable mechanism 88 designed to interconnect the free unconnected ends of the arbor support members 77. In this regard, as is best shown in FIGS. 1 and 5, the interconnecting mechanism 88 includes vertically spaced, horizontally extending, channel-shaped members 89 designed to receive associated ones of the unconnected ends of the support members 77 in telescoping relationship therein as the vertical frame moves the pallets 12 between the arbors 44 and 46. The channel-shaped members 89 are fixedly secured to one another by connecting members 91 extending vertically therebetween.

Each of the interconnecting members 89 has a laterally projecting sleeve member 92 (FIG. 5) secured thereto and slidably mounted on a vertical cylindrical post 93 secured at its upper end to one of the upper cross members 34 of the vertical frame 32 and at its lower end to the lower cross member 34 of the vertical frame. As in the case of the sleeve members 69 and 82, each of the sleeve members 92 includes a laterally projecting lug 94 engageable between laterally spaced guide flanges 96 on a collar member 97 adjustably mounted on the vertical post 93 by suitable set screws, to prevent rotation of the sleeve member and its associated interconnecting member 89 on the post.

As is best shown in FIGS. 1, 3 and 5, a pair of upstanding latch members 98 are fixedly mounted on the uppermost interconnecting member 89. The upper ends of the latch members 98 are provided with horizontally extending slots 99 (FIGS. 1 and 3) designed to receive opposite ends of a horizontal lifting bar 101 of the lifting mechanism 78 when the vertical frame 32 moves the pallets 12 into position between the arbors 44 and 46. The lifting bar 101 is apertured to receive the lower end of a vertically movable pin 102 and is adjustably mounted on the lower end of the pin by means of threaded upper and lower nut members. The pin 102 extends upward through a sleeve 103 (FIG. 3) fixedly mounted on a bracket secured to one of the members of the elevated frame 48, and is biased downward by a spring 104 in the sleeve engaged at one end with a stop member 106 secured to the upper end of the sleeve and engaged at its lower end with a bushing 107 slidable in the sleeve and secured to the pin.

A lifting cable 108 has one end thereof connected to the upper end of the vertically movable pin 102, and another lifting cable 109 has one end thereof connected to an upstanding lug 111 (left-hand side of FIG. 3) on the uppermost central arbor support member 77. Third and fourth lifting cables 112 and 113 have ends thereof connected to the brackets 71 of the uppermost arbor guide assemblies 63 and 64. As is best shown in FIG. 6, the cables 108, 109, 112 and 113 run over sheaves 114 rotatably mounted in suitable brackets on the elevated frame 48, and have their other ends connected to a traveling block 116 fixedly mounted on the outer end of a reciprocating piston rod 117 of a fluid operating cylinder 118 fixedly mounted on a suitable support on the elevated frame.

After the arbors 44 and 46 have been moved through the bores 14 in the reels 11, the operator actuates a control circuit for the lift cylinder 118, and the lift cylinder, through the cables 108, 109, 112 and 113, lifts the interconnecting mechanism 88, the central arbor support members 77 and the arbor guide and support assemblies 63 and 64 to lift the arbors 44 and 46 vertically, and thereby to lift the reels 11 off the pallets so that the reels can rotate on the arbors. The wire remnants 10 on the reels then are gathered by the operator and connected to associated winding mechanisms 119 of any suitable type at the left and right hand sides of the apparatus, as viewed in FIG. 1, and the winding mechanisms are operated to

wind the remnants thereon and thus pull the remnants from the reels.

When the arbor assemblies 22 and 23 are in their positions shown in solid lines in FIG. 2, in which the arbors 44 and 46 extend through the bores 14 in the reels 11, each of the vertical connecting members 57 and 58 engages and operates a microswitch 121 on the adjacent one of the arbor guide assemblies 63 and 64 to condition an operating circuit for the lift cylinder 118. Thus, the lift cylinder 118 cannot be operated to lift the reels 11 until the arbors 44 and 46 have been moved into position through the reels. Similarly, when each of the arbor assemblies 22 and 23 is in its retracted position shown in dashed lines in FIG. 2, each of the vertical connecting members 57 and 58 engages and operates a microswitch 122 to condition an operating circuit for the horizontally reciprocating operating cylinders 47 and 49, so that the pallets 12 and the reels 11 thereon cannot be moved into and out of position between the arbor assemblies by the cylinders until the arbors 44 and 46 have been retracted to permit such movement.

Adjacent each side of the vertical frame 32 at its top, a hook-shaped retarding bar 123 (FIGS. 1, 2 and 8) has one end fixedly mounted on the topmost one of the upper cross members 34, and has a hook element 124 at its other end which projects downward below the level of the upper surfaces of the end and side flanges 17 of the topmost pallet 12. In order that the hook elements 124 will not interfere with movement of the set of pallets 12 along the main conveyor 18 onto and off of the conveyor section 19, regardless of which pallet is the topmost pallet and which side of the topmost pallet is adjacent the vertical frame 32, the end flanges 17 of each pallet are provided with cut out portions 17a adjacent the side flanges 17 of the pallet.

As is best shown in FIGS. 3 and 8, as the pallets 12 approach the end of their movement into position on the conveyor section 19, the leading end of the topmost pallet engages a plate 126 pivotally mounted on the topmost one of the upper cross members 34, and pivots the plate upward from a depending vertical position (not shown) to a horizontal position in which it engages and operates a microswitch 127 in the operating circuit for the operating cylinders 47 and 49. The microswitch 127 is mounted on one of the retarding bars 123 which is adjacent the plate 126, as for example, as shown in FIG. 8, the retarding bar 123 at the right-hand side of the apparatus. This operation of the microswitch 127 conditions the operating circuit for the operating cylinders 47 and 49, and thus the operating cylinders 47 and 49 cannot operate to move the conveyor section 19 and the pallets in 12 between the arbors 44 and 46 until the pallets are in proper position on the conveyor section.

As the conveyor section 19 and the pallets 12 are moved between the arbors 44 and 46 by the vertical frame 32 and the operating cylinders 47 and 49, the retarding bars 123 merely move to the left (FIG. 3) above the topmost pallet 12 relative thereto. However, as the operating cylinders 47 and 49 move the pallets 12 and the conveyor section 19 from between the arbors 44 and 46 after a strand removing operation, since the pulling force is being applied to the conveyor section by the vertical frame 32 adjacent its bottom through the bolts 38, the upper operating cylinders 47 tend to move the top of the frame faster than the lower operating cylinders move its bottom, resulting in possible damage of the frame and/or the operating cylinders. To prevent this, the hook elements 124 engage the inner side of the adjacent side flange 17 of the topmost pallet 12 to distribute the pulling force and to retard the movement of the upper end of the vertical frame 32, to maintain it even with the lower end of the frame.

In operation, a set of vertically nested pallets 12 with reels 11 thereon is moved onto the conveyor section 19, as for example from the left as viewed in FIG. 2, and

an operator insures that the reels adjacent the centers of the pallets are spaced apart for receiving the support members 77 therebetween, as shown in FIGS. 2 and 4. Then, assuming that the arbor assemblies 22 and 23 are in their fully retracted positions shown in dashed lines in FIG. 2, the control circuit for the operating cylinders 47 and 49 is actuated to move the vertical frame 32 to the left as viewed in FIG. 1, and the frame moves the conveyor section and the pallets along the cross conveyor 21 between the arbor assemblies. As the conveyor section 19 and the pallets move between the arbor assemblies, the guide members 52 insure that the pallets come into engagement with the stop surfaces 56 of the stop assemblies 53. When the pallets engage the stop surfaces 56, the stop surfaces and the pallet engaging surfaces 43 on the vertical frame cooperate to align the pallets vertically such that the axes of the bores 14 in the reels 11 are parallel to the longitudinal axes of the arbors 44 and 46, and to locate the pallets so that the axes of the bores are aligned with their associated arbors. At this time, the interconnecting members 89 of the interconnecting mechanism 88 have received the unconnected ends of the arbor support members 77 to connect the ends to one another, and the horizontal slots 99 in the upstanding latch members 98 on the interconnecting mechanism have received the lifting bar 101 therein, as shown in FIGS. 3 and 5.

The arbors 44 and 46 then are moved through the bores 14 in the reels 11 to the solid line positions shown in FIG. 2. The lift cylinder 118 then is actuated and through the cables 108, 109, 112 and 113 lifts the interconnecting mechanism 88, the arbor support members 77 and the arbor guide and support assemblies 63 and 64, to lift the arbors 44 and 46 and thereby to lift the reels 11 above the V-shaped troughs 13 of the pallets 12. Next, the ends of the wire remnants 10 on the reels 11 are gathered by the operator and connected to the winding mechanisms 119, which are actuated to pull the wire remnants from the wheels.

After the wire remnants 10 have been removed from the reels 11, the lift cylinder 118 is deactivated to position the reels back on the pallets 12 in the troughs 13, and the arbors 44 and 46 are moved back to their retracted positions shown in dashed lines in FIG. 2. The operating cylinders 47 and 49 then are actuated to move the vertical frame 32, the conveyor section 19, and the pallets 12 on the conveyor section back to the position shown in FIG. 1, with the retarding bars 123 acting to prevent the upper end of the vertical frame 32 from moving faster than the lower end of the frame.

As viewed in FIG. 2, the pallets 12 then can be moved along the main conveyor 18 to the right off the conveyor section 19, whereupon another set of pallets can be moved onto the conveyor section from the left, and the above steps can be repeated.

While one embodiment of the invention has been disclosed many modifications will be apparent and it is intended that the invention be interpreted as including all modifications which fall within the true spirit and scope of the invention.

What is claimed is:

1. Apparatus for removing strands from a plurality of reels supported on pallets, which comprises:

horizontal, parallel arbors;

means for supporting said arbors;

means for moving the pallets and the reels thereon adjacent said arbors;

stop means for limiting the movement of the pallets and cooperable with said moving means to position the pallets such that the axes of bores in the reels are aligned with the longitudinal axes of said arbors, whereby said arbors can be received through the bores; and

means for lifting said arbors vertically to lift the reels off the pallets so that the reels can rotate on said

arbors and the strands can be pulled from the reels in unison.

2. Apparatus for removing strands from a plurality of reels, wherein the reels are supported on vertically nested pallets which are movable laterally relative to one another, which comprises:

vertically spaced, horizontal, parallel arbors;

means for supporting said arbors;

vertically arranged frame means engageable with the vertically nested pallets for moving the pallets and the reels thereon adjacent said arbors;

vertically arranged stop means engageable by the pallets and cooperable with said frame means to rotate the pallets about their vertical axes such that the axes of bores in the reels are aligned with the longitudinal axes of said arbors, whereby said arbors can be received through the bores; and

means for lifting said arbors vertically to lift the reels off the pallets so that the reels can rotate on said arbors and the strands can be pulled from the reels in unison.

3. Apparatus for removing strands from a plurality of reels supported on pallets, which comprises:

horizontal, parallel arbors connected together at adjacent ones of their ends for movement in unison;

guide means mounted for vertical movement and supporting said arbors for vertical movement therewith and horizontal longitudinal movement relative thereto;

means for moving the pallets and the reels thereon adjacent said arbors;

stop means cooperable with said moving means to position the pallets such that the axes of bores in the reels are aligned with the longitudinal axes of said arbors, whereby said arbors can be moved in said guide means through the bores; and

a mechanism connected to said guide means for lifting said guide means and said arbors to lift the reels off the pallets so that the reels can rotate on said arbors and the strands can be pulled from the reels in unison.

4. Apparatus for removing strands from a plurality of reels, wherein the reels are supported on vertically nested pallets, which comprises:

vertically spaced, horizontal, parallel arbors;

means supporting said arbors for longitudinal movement;

a movable support for the vertically nested pallets; a vertical frame;

means connecting said support to said vertical frame adjacent the lower end of said frame;

fluid operating means connected to said vertical frame adjacent its upper and lower ends, for moving said vertical frame into engagement with said support and the pallets to move said support and the pallets adjacent said arbors, and for moving said vertical frame, said support and the pallets away from said arbors after the strands have been removed from the reels;

stop means cooperable with said vertical frame to position the pallets such that the axes of bores in the reels thereon are aligned with the longitudinal axes of said arbors, whereby said arbors can be moved through the bores;

means for lifting said arbors vertically to lift the reels off the pallets so that the reels can rotate on said arbors and the strands can be pulled from the reels in unison; and

means cooperable with the pallets for retarding the movement of the upper end of said vertical frame away from said arbors by said fluid operating means, so that the upper end of said frame does not move faster than its lower end.

5. Apparatus for removing strands from a plurality of reels supported on pallets, which comprises:

horizontal, parallel arbors;

75

means supporting said arbors for longitudinal movement;

means for moving the pallets and the reels thereon adjacent said arbors;

stop means cooperable with said moving means to position the pallets such that the axes of bores in the reels are aligned with the longitudinal axes of said arbors, whereby said arbors can be moved through the bores;

support means located so as to extend between laterally adjacent ones of the reels as said moving means moves the pallets adjacent said arbors, and being engageable by said arbors when said arbors move through the bores in the reels, for supporting the arbors between their ends; and

a lifting mechanism for lifting said support means and said arbors, to lift the reels off the pallets so that the reels can rotate on said arbors and the strands can be pulled from the reels in unison.

6. Apparatus for removing strands from a plurality of reels, wherein the reels are supported on vertically nested pallets, which comprises:

vertically spaced, horizontal, parallel arbors;

means supporting said arbors for longitudinal movement;

vertically arranged frame means for moving the vertically nested pallets and the reels thereon adjacent said arbors;

stop means cooperable with said frame means to position the pallets such that the axes of bores in the reels are aligned with the longitudinal axes of said arbors, whereby said arbors can be moved through the bores; vertically spaced, horizontal support members connected together at adjacent ones of their ends for vertical movement and having free ends extending toward said frame means, said members being located so as to extend between laterally adjacent ones of the reels as said frame means moves the pallets adjacent said arbors, and being engageable by said arbors when said arbors move through the bores in the reels, for supporting the arbors between their ends; and

a lifting mechanism for lifting said support members and said arbors, to lift the reels off the pallets so that the reels can rotate on said arbors and the strands can be pulled from the reels in unison.

7. Apparatus for removing strands from a plurality of reels, wherein the reels are supported on vertically nested pallets, which comprises:

vertically spaced, horizontal, parallel arbors;

means supporting said arbors for longitudinal movement;

vertically arranged frame means for moving the vertically nested pallets and the reels thereon adjacent said arbors;

stop means cooperable with said frame means to position the pallets such that the axes of bores in the reels are aligned with the longitudinal axes of said arbors, whereby said arbors can be moved through the bores;

vertically spaced, horizontal support members connected together at adjacent ones of their ends for vertical movement and having free ends extending toward said frame means, said members being located so as to extend between laterally adjacent ones of the reels as said frame means moves the pallets adjacent said arbors, and being engageable by said arbors when said arbors move through the bores in the reels, for supporting the arbors between their ends;

interconnecting means mounted on said frame means for vertical movement and engageable with the free ends of said support members when said frame means moves the pallets adjacent said arbors, to interconnect the free ends of said support members; and a lifting mechanism for lifting said interconnecting

means, said support members and said arbors, to lift the reels off the pallets so that the reels can rotate on said arbors and the strands can be pulled from the reels in unison.

8. Apparatus for removing strands from a plurality of reels wherein the reels are supported on vertically nested pallets, which comprises:

vertically spaced, horizontal, parallel arbors;
means supporting said arbors for longitudinal movement;

vertically arranged frame means for moving the vertically nested pallets and the reels thereon adjacent said arbors;

stop means cooperable with said frame means to position the pallets such that the axes of bores in the reels are aligned with the longitudinal axes of said arbors, whereby said arbors can be moved through the bores;

vertically spaced, horizontal support members connected together at adjacent ones of their ends for vertical movement and having free ends extending toward said frame means, said members being located so as to extend between laterally adjacent reels on said pallets as said frame means moves the pallets adjacent said arbors, and being engageable by said arbors when said arbors move through the bores in the reels, for supporting the arbors between their ends;

interconnecting means mounted for vertical movement on said frame means and engageable with the free ends of said support members when said frame means moves the pallets adjacent said arbors, to interconnect the free ends of said support members; and

a lifting mechanism, including means for engaging and connecting said interconnecting means to said lifting mechanism as said frame means moves the pallets adjacent said arbors, said lifting mechanism being operative to lift said interconnecting means, said support members and said arbors to lift the reels off the pallets so that the reels can rotate on said arbors and the strands can be pulled from the reels in unison.

9. Apparatus for removing strands from a plurality of reels, wherein the reels are supported on vertically nested pallets, which comprises:

vertically spaced, horizontal, parallel arbors connected together at adjacent ones of their ends for movement in unison;

guide means mounted for vertical movement and supporting said arbors for vertical movement therewith and horizontal longitudinal movement relative thereto;

a conveyor extending adjacent said arbors;

a vertical frame engageable with the vertically nested pallets for moving the pallets and the reels thereon along said conveyor;

vertically arranged stop means engageable by the pallets and cooperable with said vertical frame to position the pallets such that the axes of bores in the reels are aligned with the longitudinal axes of said arbors, whereby said arbors can be moved through the bores in the reels;

vertically spaced, horizontal support members located above said conveyor so as to extend between adjacent ones of the reels when said vertical frame moves

the pallets along said conveyor, and being engageable by said arbors when said arbors move through the bores in the reels, for supporting the arbors between their ends;

means for lifting said support members and said guide means and thereby lifting said arbors to lift the reels off the pallets so that the reels can rotate on said arbors; and
rotatable means connectable to the strands for pulling the strands from the reels in unison.

10. Apparatus for removing strands from a plurality of reels, wherein the reels are supported on vertically nested pallets which are movable laterally relative to one another, which comprises:

a main conveyor for transporting the pallets and the reels;

vertically spaced, horizontal, parallel arbors connected together at adjacent ones of their ends for movement in unison;

guide means mounted for vertical movement and supporting said arbors for vertical movement therewith and horizontal longitudinal movement relative thereto;

a cross conveyor extending adjacent said main conveyor and said arbors, said main conveyor having a section thereof supported for movement on said cross conveyor;

a vertical frame mounted for horizontal movement above said cross conveyor;

lost motion means connecting said vertical frame and the conveyor section;

means for moving said vertical frame into spaced relationship with respect to the conveyor section so that the vertically nested pallets can be moved onto the conveyor section, and for moving said frame into engagement with the conveyor section and the pallets to move the conveyor section and the pallets along said cross conveyor;

vertically arranged stop means engageable by the pallets and cooperable with said vertical frame to rotate the pallets about their vertical axes and to align the pallets vertically such that the axes of bores in the reels thereon are aligned with the longitudinal axes of said arbors, whereby said arbors can be moved through the bores;

vertically spaced, horizontal support members extending above said cross conveyor so as to extend between adjacent ones of the reels when said vertical frame moves the pallets along said cross conveyor, and being engageable by said arbors when said arbors move through the bores in the reels, for supporting the arbors between their ends;

means for lifting said support members adjacent their opposite ends, and for lifting said guide means, and thereby lifting said arbors to lift the reels off the pallets so that the reels can rotate on said arbors; and
rotatable means connectable to the strands for pulling the strands from the reels in unison.
